SLOPELINE APPROACH LIGHT SYSTEM

James E. Davis, Arcata, Calif.

Application March 25, 1954, Serial No. 418,793

6 Claims. (Cl. 340—26)

(Granted under Title 35, U. S. Code (1952),
sec. 266)

1

The invention described herein may be manufactured and used by or for the Government of the United States of America for governmental purposes without the payment of any royalties thereon or therefor.

The present invention relates to a slopeine approach light system and more particularly to slopeine approach light system which incorporates single dimension ground-plane and direction-of-flight elements into the three dimensional elevation-and-centerline-deviation and horizontal-and-distance elements.

The standard slopeine approach light system consists of two converging rows of slopeine light units lying to the right and left of the runway axis, beginning 3000 feet from the runway threshold and ending at a point 200-300 feet therefrom. The point of convergence of the two rows occurs near the ideal touchdown point on the runway centerline. The individual slopeine units are mounted in vertical planes perpendicular to the runway axis and are spaced at 100 foot intervals. The major dimension of each unit slopes toward the ideal glide path at an angle of 45 degrees with respect to the plane of the runway. The transverse location of the individual units is determined by the intersection of the two 45 degree planes, which pass through the ideal glide path, with the local terrain. Three transverse bars were added to the original slope line system to provide additional horizontal reference and to establish three check points to inform the pilot of his distance from the runway threshold.

The disadvantage of the standard system is that neither the original system nor the transverse bar additions provide a fixed ground plane with reference to the individual slope units, the only fixed reference for the pilot being an imaginary line he draws from the base of one unit to the base of the next unit. The series of slope units tend to break up when the pilot is off of the ideal glide path and becomes confusing particularly during low visibility approaches when he has only a few units of one side in view and is off the ideal glide path. Under these conditions there is not enough ground plane and direction of flight information present and the pilot may make the wrong correction, thereby necessitating a new approach attempt. In the standard system there is no fixed reference for the slopeine units to oscillate around or pivot from. This leaves the pilot with the impression of a series of objects in space with no tie point to indicate a ground plane or solid substance ahead on which to land the airplane.

2

The present invention overcomes the disadvantages of the prior known systems by incorporating single dimension ground-plane and direction-of-flight elements into the three dimensional elevation-and-centerline-deviation and horizontal-and-distance elements. This is accomplished by increasing the spacing between adjacent slope units and positioning individual lamp light units at short intervals along the ground plane therebetween, so as to form a straight line of light units extending from the base of one slope unit away from the threshold approximately half way towards the next slope unit. The single light units lie in the ground plane and provide artificial ground-plane and direction-of-flight guidance even though the pilot may not readily interpret the elevation and lateral guidance afforded by the slope units. The lines of light units provide fixed elements in the system that the top ends of the slope units can oscillate around and the bottom ends can pivot from, thus giving the pilot a sensation of substance rather than merely something in space.

An object of the present invention is the provision of a slopeine approach light system which includes tie points for the slopeine units.

Another object is to provide direction of flight guidance in a slopeine approach light system.

A further object of the invention is the provision of well defined ground plane guidance in a slopeine approach light system.

An additional object of the present invention is the provision of a three dimensional slopeine approach light system which embodies single dimension ground-plane and line-of-flight elements.

Other objects and many of the attendant advantages of this invention will be readily appreciated as the same becomes better understood by reference to the following detailed description when considered in connection with the accompanying drawings wherein:

Fig. 1 is a plan view of the threshold of a runway and an approach light system according to the present invention.

Fig. 2 is an elevation view of the system of Fig. 1.

Fig. 3 is an elevation view of a slopeine light unit used in the present invention.

Figs. 4-7 are schematic perspective views showing the patterns made by the approach lights as seen from an approaching aircraft when it is respectively high on centerline, low on centerline, high and to right of glide path, and on glide path.

Referring more particularly to the drawings,

Fig. 1 shows the threshold of a runway 11 and two rows of approach lights 12 and 13 diverging away therefrom on either side of the runway centerline. Each of the rows 12 and 13 consists of alternately arranged 45 degree slopline units 14 and groups of individual light units 15 and extends approximately 3000 feet from the runway threshold. The 45 degree slopline units are spaced approximately 200 feet apart and each group of individual lights forms a line extending from the base of one slopline unit away from the runway threshold approximately halfway to the next slopline unit. Each group of individual lights usually consists of seven lights spaced 15 feet apart, the first one of which is also positioned 15 feet from the base of a slopline unit, the group of lights thus forms a line approximately 105 feet long. The spacing between individual lights or the number of individual lights in a group may be varied to satisfy the requirements of any individual approach area, but the individual lights of each group must all be positioned on a line extending between the bottom lamps of adjacent slopline units.

Fig. 2 shows an elevation view of one line of approach lights in which the approach area on which the row is positioned is flat. In this view, the individual light units are all in the same horizontal plane with the bottom lamps of adjacent slopline units. If the approach area were uneven and one slopline unit at a higher elevation than the adjacent slopline unit, the individual lights positioned therebetween would all be mounted so as to be in the plane joining the bottom lamps of adjacent slopline units. If the difference in elevation between adjacent slopline units exceeds approximately 5 feet it may be necessary to add additional lights to the group in order to retain the continuity of the system.

The 45 degree slopline unit of Fig. 3 consists of a vertical upright 16 on which is secured a crosspiece 17 at an angle of 45 degrees with the horizontal. A plurality of lamps 18 are spaced along the length of the crosspiece. The slopline units are arranged in pairs, one in each row of lights, and the intersection of the extensions of the lines defined by the lamps on the crosspieces marks the location of the ideal glide path.

The groups of individual light units provide direction of flight and ground plane guidance which is not supplied by the slopline units. As shown in Figs. 4-7, this guidance does not depend upon the position of the approaching aircraft, but exists for all positions during an approach. When the approaching aircraft is on the ideal glidepath, the groups of individual lights and the slopline units merge into almost continuous straight rows. When the approaching aircraft is off of the ideal glidepath, the rows of light units become segmented and each slopline unit appears to pivot about its associated group of individual light units. The slopline units point inwardly when the aircraft is high on centerline, Fig. 4, and outwardly when the aircraft is low on centerline, Fig. 5. When the aircraft is not on the centerline and is high, Fig. 6, the farther row becomes segmented and the slopline units of the nearer row point inwardly. As can be seen from Fig. 5, a pilot low and to one side of the glidepath would see the slopline units of the farther row point outwardly and those of the near row overlap the adjacent groups of individual lights. As can be seen from Figs. 4-7, the lines formed by the individual light units

appear to merge at the touchdown point on the runway regardless of where the approaching aircraft is in relation to the ideal glidepath. In addition, these lines remain fixed on the ground and do not appear to rotate or pivot as do the lamps on the slopline units, the ground plane is therefore defined at all times. Since the rows of light units are off the centerline of the approach area they are not obscured by the engine of a single engine aircraft or the nose of a multi-engine aircraft and they therefore provide two lines of approach lights for the pilot to follow even though he does not interpret the elevation guidance inherent in the slopline units.

Obviously many modifications and variations of the present invention are possible in the light of the above teachings. It is therefore to be understood that within the scope of the appended claims, the invention may be practiced otherwise than as specifically described.

What is claimed is:

1. An aircraft landing aid system including two straight rows of lighting elements converging towards the threshold of a landing strip, each of said rows comprising alternately positioned 45 degree slopline light units and lines of spaced single light units, each of said lines of single light units extending from the base of one slopline unit away from the threshold approximately halfway to the next slopline unit; whereby the lines of single light units provide fixed elements which the tops of the slopline units oscillate around and the bottoms thereof pivot from.
2. An aircraft landing aid system including two straight rows of lighting elements converging towards the threshold of a landing strip, each of said rows comprising a plurality of 45 degree slopline light units spaced at large intervals; a plurality of single light units spaced at short intervals positioned between each pair of slopline units, said plurality of single light units forming a line extending from the base of one slopline unit away from the threshold towards the next slopline unit; whereby each line of single light units forms a fixed element about which the top of the associated slopline unit can oscillate and from which the bottom thereof can pivot.
3. In an aircraft landing aid system including two straight rows of spaced 45 degree slopline light units converging towards the threshold of landing strip, the improvement comprising a line of spaced single light units positioned between each pair of slopline units, each line of single light units extending from the base of one slopline unit away from the threshold approximately halfway to the next slopline unit; whereby each line of single light units forms a fixed element about which the top of the associated slopline unit can oscillate and the bottom thereof can pivot.
4. In a slopline approach light system including two rows of 45 degree slopline light units converging towards the threshold of a landing strip, the slopline units of each row being spaced at large intervals, the improvement consisting of a plurality of single light units spaced at short intervals positioned between each pair of slopline units, said plurality of single units forming a line extending from the base of one slopline unit away from the threshold towards the next slopline unit; whereby the lines of single units provide ground-plane and line-of-flight guidance for an approaching aircraft.
5. A slopline approach light system comprising

ing two converging rows of alternately positioned 45 degree slopeine units and lines of single units, each of said lines comprising a plurality of relatively closely spaced single units, said slopeine units being spaced at twice the normal interval with each line of single units extending from the base of one slopeine unit in divergent fashion approximately halfway to the next slopeine unit; whereby each line of single units forms a fixed element about which the top of the associated slopeine unit can oscillate and from which the bottom thereof can pivot.

6. In a standard slopeine approach light sys-

tem including two convergent rows of 45 degree slopeine light units with alternate slopeine units of each row removed, the improvement consisting of a plurality of relatively closely spaced single light units positioned between each pair of slopeine units, each group of single units forming a line extending from the base of one slopeine unit in divergent fashion approximately halfway to the next slopeine unit; thereby providing ground-plane and line-of-flight guidance for an approaching aircraft.
